UNITED STATES PATENT OFFICE.

NATHAN H. LONG, OF MUNCIE, INDIANA.

CLOTHES-RACK.

SPECIFICATION forming part of Letters Patent No. 288,645, dated November 20, 1883.

Application filed April 14, 1883. (No model.)

To all whom it may concern:

Be it known that I, NATHAN H. LONG, a citizen of the United States, residing at Muncie, in the county of Delaware and State of Indiana, have invented a new and useful Improvement 5 in Clothes-Racks, of which the following is a specification.

My invention relates to improvements in clothes-racks; and the objects of my improvements are to construct a cheap and convenient adjustable rack for drying clothes. I attain these objects by the mechanism illustrated by the accompanying drawings, in which—

Figure 1 is a perspective view of my invention ready for use. Fig. 2 is an end view, showing the racks adjusted in different positions; and Fig. 3 is a view showing the rack folded up ready for shipping.

The legs *a* are hinged together by a strap, 20 *i*, so that they may be spread apart, as shown in Figs. 1 and 2. The upper parts of the said legs are provided with notches *d*, as shown. The legs *a* are held apart by the rounds *e*. The

racks *e b* are hinged at the top of the legs by rods *f*, as shown, and the arms *b* are held 25 apart by rounds *e*, similar to those in the legs *a a'*. The inner ends of the arms *b* are rounded off, so that they will fit in the notches *d*, as shown. The said arms are also provided with a hook and eye, *s s'*, so that the rack may be 30 held together when folded up, as shown in Fig. 3; or the said hooks *s s'* may be left off, if desired. As thus constructed, the racks *b e* may be 35 adjusted in various positions, and the articles to be dried are placed on the rounds *e e'*.

Having thus described my invention, I claim the following and desire to secure the same by Letters Patent—

In a clothes-rack, the combination of the legs *a a'*, rounds *e e'*, arms *b*, rods *f*, bars *i*, 40 and notches *d*, all for the purpose set forth.

NATHAN H. LONG.
